(57) **CLAIM**

The ornamental design for a pistol sight, as shown and described.

DESCRIPTION

FIG. 1: is a perspective view of a pistol sight in one embodiment thereof.

FIG. 2: is a back view of a pistol sight in one embodiment thereof.

FIG. 3: is a front view of a pistol sight in one embodiment thereof.

FIG. 4: is a left view of a pistol sight in one embodiment thereof.

FIG. 5: is a right view of a pistol sight in one embodiment thereof.

FIG. 6: is a bottom view of a pistol sight in one embodiment thereof; and,

FIG. 7: is a top view of a pistol sight in one embodiment thereof.

The present design is embodied in a pistol sight that may be presented as an accessory for pistols.
